In Germany May 25, 1935

1 Claim. (Cl. 88—20)

I have filed an application in Germany, May 25, 1935.

The invention concerns a device for measuring the albumen in the aqueous humour of the anterior chamber of an eye to be examined, determinations of the changing proportion of albumen in the said humour being indicative of the progress of an inflammation of the iris. According to the invention, a lamp is used which images an illuminated slit on the eye part to be examined, and the luminous intensity of a portion of the pencil of light is weakened by optical means until the luminous intensity of the Tyndall effect produced by this weakened light in the cornea corresponds to that of the Tyndall effect produced by the unweakened portion of the said pencil in the aqueous humour of the anterior chamber of the eye. As the proportion of albumen in the cornea can be assumed to be constant enough in such an examination of the eye, the luminous intensity of the Tyndall effect can be considered as sufficiently constant also within the cornea, and as this intensity is substantially greater than the luminous intensity of the Tyndall effect in the aqueous humour of the anterior chamber, the magnitude of the weakening of the light provides a measure for the determination of the proportion of albumen in the aqueous humour. Experiments have proved that a change in the proportion of albumen can increase the luminous intensity of the Tyndall effect in the aqueous humour of the anterior chamber to a thousand times its lowest magnitude. It is therefore appropriate to equip the slit lamp for the examination with a light-absorbing plate of changeable effective thickness, and to provide that this plate can reduce to a thousandth the luminous intensity of part of the pencil of light emanating from the lamp, the said light-absorbing plate conveniently consisting of two wedges of grey glass which can be moved relatively to each other. Instead of one light absorbing plate of changeable effective thickness, use can be made of a plurality of plates which have different light absorbing capacities and are attached to the slit lamp by means of a changing device. These light-absorbing plates are graded conveniently from 0 to 3 photopters. Photopters are units which have been used by Professor Tscherning for determining the absorption capacity of grey glasses, glass of one photopter absorbing 90%, or being traversed by one tenth, of the light, glass of two and three photopters being traversed by one hundredth and one thousandth of the light, re-

spectively. It is especially convenient to use light-absorbing plates graded according to quarters of a photopter, since the unavoidable measuring errors are below a damping magnitude of one quarter photopter. The device for changing these plates of different light absorbing capacities may be a slide which contains different plates of grey glass next to each other and is introduced into a guide in the housing of the slit lamp, or it may be a rotatable disc in which the grey-glass plates are radially disposed.

The instrument according to the invention is illustrated by way of example in the accompanying drawings.

Figure 1 represents this instrument schematically, partly in section.

Figure 2 is a view of the changing device provided with light-absorbing glass plates.

Figure 3 represents on a larger scale the path of the light rays emitted by the source of light and shown in Figure 1.

Figures 4 and 5 show the microscopically viewed luminous field of the light pencil in the cornea and in the aqueous humour of the anterior chamber of the eye, the lower part of the pencil of light which enters the eye being less weakened by a grey glass placed in this part of the pencil of light than the corresponding part of the pencil of light in Figure 5.

For the determination of the proportion of albumen in the aqueous humour of the anterior chamber of an eye, there is used according to Figure 1 a Gullstrand slit lamp whose source of light 1 is imaged by means of a two-lens condenser 2 at the locus of a convergent lens 4 held by a bracket 3. By means of the lens 4 of the slit lamp, a slit 5 in the path of the rays is imaged on that part of the eye 6 which is to be examined, this part being viewed by means of a binocular microscope 8 having two objectives 7. In front of the slit 5, the front wall 9 of the lamp housing 10 is provided with a changing device constituted by a disc 11 which is rotatable about a pin 12 and has thirteen radially disposed slits 13. Each of the slits 13, a slit 13' being excepted, is partially covered by a plate 14 of grey glass, so that only a definite part of the pencil of rays traversing each of these slits 13 can proceed unweakened from the slit lamp. The transparencies of the plates 14 are graded according to quarters of a photopter from $\frac{1}{4}$ to 3 photopters. The damping magnitudes of the plates 14 are indicated in photopters on round glass plates 15 between the slits 13. In the front wall 9 of the lamp housing 10, and near the slit 5, is provided a window 16.

in which there appears the number plate 15 corresponding to the plate 14 in front of the slit 5 and illuminated by the source of light 1. Accordingly, an observer can read direct, at any time, the photopter magnitude corresponding to the plate 14 in front of the slit 5.

When the instrument is to be used, the source of light is switched on, and the eye 6 to be examined is given such a position that the pencil of light 10 enters the anterior chamber 17 of the eye and the real image of the slit is projected approximately on the front surface 18 of the eye lens. The section of the eye 6, which is illustrated in Figure 1, as well as a plane containing the axes of the two microscope objectives 7 lie in reality in a plane at right angles to that of the drawings, which contains the principal axis of the slit lamp. By means of a plate 14 of grey glass in front of the slit 5, the part of the pencil 15 of rays traversing this plate is damped and therefore easily distinguishable by its reduced luminous intensity from the other part of the ray pencil traversing the slit 13 (cf. Figure 3). Each of the parts *a* and *b* of the light beam produces a Tyndall effect in the cornea 19 as well as in the aqueous humour in the anterior chamber 17. The proportion of albumen is now ascertained by turning the disc 11 by hand until such a plate 20 of grey glass is in front of the slit 5 as damps 25 the luminous intensity of the Tyndall effect in the cornea 19 so much that this intensity is the same as the luminous intensity of the Tyndall effect of the undamped pencil of light in the aqueous humour in the anterior chamber 17. Figures 4 30 and 5 illustrate in the cornea and in the aqueous humour of the eye 6 the microscopic view of the luminous field of the pencil of light passing 35 through the slit 13. For the sake of a clear representation of the pencil of light, the slit is assumed to be quadrilateral. In Figure 4, the pencil of light in the albuminous humour 17 is still darker than that in the cornea 19, so that the grey glass placed into the ray path is not yet dark enough. The correct grey glass is used in Figure 5, in which the pencils of light in the aqueous humour 17 and in the cornea 19 are equally bright. Subsequently thereto, the damping magnitude is read in the window 16, this 10 magnitude being a measure for the proportion of albumen in the aqueous humour of the anterior chamber of the eye under examination.

I claim:

An instrument for measuring the albumen in the aqueous humour of the anterior chamber of an eye to be examined, comprising a light source, a slit diaphragm receiving the rays emanating from said light source, an optical system imaging said slit on the front surface of the lens of the eye under examination, a disc having radially disposed openings rotatably mounted on a pin lying outside the ray path, said disc being close to said slit diaphragm and adapted to be rotated so as to align the respective openings with the slit diaphragm, the axis of said pin being parallel to the axis of said optical system, the axis of rotation of said disc being substantially equidistant from the center of said openings and the axis of said optical system, a plurality of light absorbing plates of different densities, one plate being mounted in each of said openings, each of said plates being of smaller area than the respective openings in the disc thereby providing an unobstructed path for a portion of the rays, and 20 means for indicating the light-absorbing capacity of said plates.

HENNING RÖNNE.
